METHOD OF AND APPARATUS FOR PRE-COOLING LOADED CARS

Peter Nalbandian, Fresno, Calif., assignor to Improved Carloading Company, Fresno, Calif., a copartnership composed of Peter Nalbandian and D. D. Byrnes

Application March 19, 1945, Serial No. 583,517

7 Claims. (Cl. 62—24)

1

This invention relates to a method of pre-cooling perishable packaged goods such as vegetables, fruit, etc., after the same has been loaded into refrigerator cars for transit to the place of unloading.

Conventional refrigerator cars have air cooling compartments such as ice bunkers or the like at opposite ends of the car, which compartments communicate by means of upper and lower openings therein with the interior of the car at points adjacent the floor and roof. The load is generally supported by a perforated false floor spaced above the main floor for movement of air therethrough and to the lower opening, while the top opening in each compartment is generally sufficiently high to be above the load. In normal circulation the cooled air moves from the lower openings in the end bunkers or compartments into the space below said false floor and toward the center of the car, it rises through the apertures in the floor for cooling the load and then moves back to the cooling compartments through the upper openings in the latter. Ordinarily such circulation is not forced.

In order to insure adequate refrigeration, particularly in relatively long trips, and to reduce or eliminate the necessity for re-icing cars en route, the load is precooled at the starting point to reduce the temperature to the point where it may be maintained satisfactorily over a long distance of travel by filled ice bunkers.

It is customary to effect this precooling by fans positioned to direct air from the upper openings in the cooling compartments generally laterally over the load of packaged goods. This method reverses the normal circulation of air and is adopted for the reason that the top portion of the load is the most difficult to cool. The lower packages in the load are in a naturally created cold air zone in the car that quickly forms due to natural convection but the top half of a normal load is not in such zone. This directing of the air laterally over the top of the load is not particularly satisfactory irrespective of the manner in which the car is loaded and is particularly inefficient where the load is in vertical, horizontally spaced stacks, as in the Hoak United States Patent Re. No. 22,256, of January 26, 1943, or in Chalmer's United States Patent No. 1,820,729, of August 25, 1931. In these instances the air tends to merely move over the tops of the stacks without entering the vertical passageways between stacks.

The main object of this invention is to provide a cheap and effective method for precooling

2

packaged perishable goods in cars, and particularly such goods as are in packages that are in spaced stacks providing vertical passageways between stacks.

5 Another object of the invention is to provide a combination of elements for more efficiently precooling packaged perishable goods in a car.

Other objects and advantages will appear in the description and drawings.

10 In the drawings:

Fig. 1 is a semi-diagrammatic view illustrating the method, and which view is taken longitudinally through a loaded car, the car walls being indicated in section.

15 Fig. 2 is a fragmentary enlarged horizontal sectional view taken through one end portion of a car illustrating a preferred method of spacing the stacks apart to provide vertical passageways between them.

20 Fig. 3 is a fragmentary enlarged vertical sectional view through part of a car showing in elevation the tiers and stacks of packages and the spacers that may be employed.

Fig. 4 is a semi-diagrammatic view illustrating 25 a modification of the method shown in Fig. 1.

In detail, the method herein disclosed may include the initial step of loading a car 1 with lug boxes 2 or the like, that contain the perishable goods to be precooled. The said boxes are arranged in spaced vertical stacks that are generally designated 3.

One means that may be used in the loading of the car for spacing the stacks in the preferred manner is posts 4 (Figs. 2, 3) that are respectively provided with cross-pieces 5 that are secured to one side of each post and that project oppositely laterally therefrom. The posts 4 are preferably positioned between the adjacent pairs of stacks in the rows thereof that extend across

40 the width of the car, while the pieces 5 are preferably between the adjacent pairs of stacks in the rows thereof extending longitudinally of the car. Such cross-pieces may also space the end rows of the stacks from the end walls 6 of the car adjacent said end rows, while posts 7 may space the stacks of side rows from the sides 8 of the car. Pieces 9 projecting laterally from one side only of such posts 7 may space the adjacent pairs of stacks in the side rows from each other.

45 In a loaded car the stacks 3 in the car are ordinarily in two groups, one group being in one end of the car and the other group being in the opposite end. These two groups are spaced apart by spacing timbers 10 in the central space 50 between said groups adjacent the car doors 12.

The main object of this invention is to provide a cheap and effective method for precooling

In Fig. 1 the spacers between the stacks 3 are not indicated in order to more clearly illustrate the method, it being understood that in the preferred form the spaces 13 (Fig. 3) between the cross members 5 provide horizontal passageways between the rows of stacks that extend crosswise of the car, while the vertical passageways 14 (Fig. 1) comprise the vertical passageways between the adjacent pairs of stacks in each of the rows that communicate with passageways or spaces 13. The upper open ends of said passageways are indicated at 14 in Fig. 2. The spaces between the adjacent rows of stacks that extend longitudinally of the car provide vertical passageways 15 (Fig. 4).

The posts 4 preferably project above the top of the load (Fig. 3) for a reason to be described, which contributes to the result desired but is not absolutely essential to providing results improved over the heretofore practiced method.

At the opposite ends of the car are the conventional cooling compartments 16 that may contain ice, said compartments communicating with the interior of the car at their upper ends through opening 17 in each end, and communicating with the lowermost portion of the interior of the car through openings 18 in each end.

A fan 19 is in each upper opening 17, the said fan being directed generally laterally, but slightly downwardly, and being operable for sucking cold air from compartment 16 and blowing it into the car and slightly downwardly.

These fans are not new, being heretofore employed for precooling by blowing the cold air across the load. However, as already explained, this old method is not economical or satisfactory, particularly with the load above described inasmuch as the cold air does not tend to go into passageways 14, 15.

The lug boxes carrying fruit or the like, ordinarily have imperforate end walls, while the tops 20 are bowed upwardly between said end walls (Fig. 3) thereby providing relatively free access of air to the fruit in the boxes, or to the thin curtain material sometimes used below such top for covering the fruit. Thus it is seen that if the air streams indicated by the arrows 21 (Fig. 1) were in some degree to be controlled so as to pass downwardly into passageways 14, thus air would relatively quickly cause cooling of the contents of the boxes as it would come in fairly intimate heat exchange relation to said contents and would also circulate laterally through spaces 13.

By placing fans 22 adjacent the car roof and below it and in positions to intercept or deflect air streams 21 downwardly through the downward blasts 23 of air from said fans 22, an appreciable amount of the air in streams 21 is forcibly deflected into the passageways 14. Inasmuch as fans 22 merely circulate car air there is no injection of outside air into the car, and the influence of said fans is sufficient to effectively cause a precooling of the contents of the stacks even where only a single fan is used about midway between the space 11 and each end 6 of the car. Obviously any number of such fans may be used and the same may be of the oscillating type. However, in any instance, the same should function to intercept and deflect the cold air coming from the cooling compartment into the passageways 14.

In the past another method of precooling has been used rather than relying on the fans 19, and this method is illustrated diagrammatically

in Fig. 4, which figure also shows my improved method.

The car 1 is loaded in the same manner as the car of Fig. 1. However, the cold air from the ice compartments is drawn from the lower openings in said compartments toward the door where a circulating fan 25 blows the air over the top boxes in the load to the upper opening 26 in each end of the car. The fans 22 above the load blow of this air downwardly into passageways 13, 14 between stacks. The principal difference between this method and that illustrated in Fig. 1 is that the movement of the air to and from the ends of the car is reversed in direction.

The apparatus used in Fig. 4 may be centrally of the car with the fan or blower 25 outside the car and communicating with the interior of the car through closure conduit 39 that closes the car door against admission of atmospheric air into the car. A partition 31 may be used for drawing the lower strata of air in the car from the lower openings in the ends to the fan for ejection above the partition back into the upper half of the car for movement to each upper opening 26.

The projection of posts 4 above the load assists in the circulation of air by deflecting some of the air striking said upper ends into passageways 15. This air helps lower the temperature, although it is manifest that the air deflected into passageways 14 causes the major portion of the result independently of the passageways 15.

The drawings and description are merely illustrative of the preferred form of the invention and are not to be considered restrictive thereof.

I claim:

1. The method of precooling packaged perishable goods in a car that comprises the steps of arranging the packages of such goods in spaced stacks providing vertical passageways between stacks, then moving a stream of cold air laterally over the upper ends of said stacks and intercepting such stream by a downward blast of air from above said stream and passageways for causing cold air from said stream to move downwardly into said passageways.

2. The method of precooling packaged perishable goods in a car that comprises the steps of arranging the packages of such goods in spaced stacks providing vertical passageways between stacks, closing said car, circulating a stream of air in the closed car over a cooling medium and then over the tops of said stacks and back to said medium, intercepting said stream by a downward blast of car air from a point above the upper ends of said passageways for movement of said blast and air from said stream into said passageways, causing said air so moved into said passageways to move over said cooling medium for cooling and for re-entering said stream.

3. The method of precooling packaged perishable goods in a car that comprises the steps of arranging the packages of such goods in a pair of spaced groups of spaced stacks with one of said groups in each end of the car and with the stacks in each group so arranged as to provide vertical passageways between them, closing said car, circulating separate streams of air in the closed car over cooling mediums at opposite ends of said car and then in direction over the upper ends of said passageways toward the space between said groups and then back to said cooling medium, causing downward blasts of car air from

above said open ends of said passageways of said groups to deflect cold air from said separate streams into said passageways for passage downwardly therethrough and moving the air from said blasts with the air so deflected back to said cooling medium for recooling.

4. In combination with a refrigerator car provided with air cooling compartments at its opposite ends each provided with an upper and a lower opening communicating with the interior of the car at points adjacent the roof and floor, an air circulating fan in each upper opening arranged for directing cold air from said compartments laterally over the top of a load in said car, a load in said car comprising vertical spaced stacks of packaged goods providing vertical passageways between said stacks, air moving means adjacent the roof of said car and within the latter for moving air so directed from said fans downwardly into said passageways.

5. In combination with a refrigerator car provided with air cooling compartments at its opposite ends each provided with an upper and a lower opening communicating with the interior of the car at points adjacent the roof and floor, an air circulating fan in each upper opening arranged for directing cold air from said compartments laterally over the top of a load in said car, a load in said car comprising vertical spaced stacks of packaged goods providing vertical passageways between said stacks, air moving means adjacent the roof of said car and within the latter for moving air so directed from said fans downwardly into said passageways, said air moving means comprising downwardly directed fans disposed over the said stacks and over said passageways.

6. In combination with a refrigerator car,

means for cooling the air in said car, means for circulating the air so cooled generally horizontally in the upper half of one end of said car in one direction and generally horizontally in the

5 opposite direction in the lower half, means for deflecting the air so moved in said upper half downwardly into the air in said lower half for moving such air into a load adapted to be positioned in said lower half, said last mentioned 10 means comprising downwardly directed air fans within said car, and the said means for cooling said air being positioned for engaging said air immediately prior to movement thereof in said upper half.

15 7. In combination with a refrigerator car, means at opposite ends of said car for cooling the air in the latter, means for circulating the air in said car generally horizontally in the upper half of said car from said means toward the center of said car and from said center downwardly

20 and back to said means for recooling, downwardly directed fans within said car adjacent the roof and between said ends and the center of said car for deflecting downwardly air so moved in

25 said upper half whereby a load on the floor of such car and in said lower half will be cooled by the air so deflected.
